RETAINING MEMBER FOR STRAPS

Herbert Harvey, Los Angeles, Calif., assignor to
Leo M. Harvey, Los Angeles, Calif.

Application December 23, 1936, Serial No. 117,303

3 Claims.

(Cl. 1—56)

This invention relates to securing and fastening devices and relates more particularly to stays or straps for securing and binding boxes, cartons, crates, etc. A general object of this invention is to provide practical and improved straps of the character mentioned that are adapted for application or driving by a stapling machine.

Another object of this invention is to provide straps that are formed or shaped to be readily fed through the staple guides of a stapling machine and to automatically swing to the proper position for driving upon reaching the ends of the guides.

Another object of this invention is to provide stays or straps of the character mentioned that are formed so that their barbs do not tend to pull loose when the straps are subjected to shock or in the event of working or moving of the box or crate parts during shipping or due to shrinkage of the contents of the crate.

Another object of this invention is to provide stays or straps of the character mentioned having integral parts engageable by machine elements to orient the straps when their barbs are bent and sharpened and engageable by elements of the stapling machine to guide, orient, turn or otherwise manipulate the straps during their application or driving.

Another object of this invention is to provide improved stays or straps of the character mentioned in which the parts engaged by the machine elements are spaced from the barbs so that the barbs at the ends of the straps may remain free or exposed when the straps are in the stapling machine.

Another object of this invention is to provide stays or straps of the character mentioned that are simple and inexpensive, constituting single integral lengths of wire.

Another object of this invention is to provide straps of the character mentioned that are adapted to closely nest together in a compact assembly or gang for ready insertion in the stapling machine.

Another object of this invention is to provide straps of the character mentioned in which the projecting parts referred to above cooperate one with the other to hold the straps oriented when in a gang and to prevent relative movement between the straps of the gang.

Another object of this invention is to provide an assembly or gang of nested stays or straps of the character mentioned held in proper nested relation by novel means that are readily remov-

able when the straps are positioned or inserted in the stapling machine.

Another object of this invention is to provide practical and effective means for holding a multiplicity or gang of stays or straps together for shipping, handling and for ready insertion in a stapling machine.

Another object of this invention is to provide an assembly or gang of staples of the character mentioned in which the projecting parts of the straps cooperate with binding members to prevent displacement of the straps from the gang and to maintain the staples in their proper relation in the gang or assembly.

The various objects and features of my invention will be fully understood from the following detailed description of typical preferred forms and applications of the invention, throughout which description reference is made to the accompanying drawing, in which:

Fig. 1 is a side elevation of a gang or assembly of one form of straps of the present invention held in the assembled relation by the binding members of the invention. Fig. 2 is a bottom plan view of the assembly illustrated in Fig. 1. Fig. 3 is a perspective view of one of the straps of the type illustrated in Figs. 1 and 2. Fig. 4 is an enlarged fragmentary side elevation of one of the said straps. Fig. 5 is a fragmentary elevation view of one of the said staples illustrating the configuration of one of the projecting portions. Fig. 6 is a bottom elevation of another form of strap of the invention and Fig. 7 is an enlarged end view of one of the binding members.

The present invention provides an assembly of a multiplicity of nested box or crate stays or straps and improved means for holding the gang of straps together in the nested relation. The several straps of the assembly or gang are identical and I will first describe a single strap of one form of the invention and will then describe the means for holding the multiplicity of straps together in the nested relation. It is to be understood that the following detailed description of one of the straps of the invention is applicable to the other straps of the gang or assembly.

The improved staple or strap of the present invention illustrated in detail in Figs. 3, 4, and 5 comprises, an elongate body 10, barbs 11 on the ends of the body 10 and laterally projecting portions 12 on the body 10.

In accordance with the invention the improved strap may be formed of a single integral rod or length of wire. The body 10 constitutes the major or principal portion of the strap. The body

20

10 is of substantial length, the length of the body of course depending upon the size of the strap and the intended use or application of the strap. In accordance with the invention the body 10 5 may be straight and plain except for the laterally projecting portions 12 to be hereinafter described.

The barbs 11 are integral terminal or end portions of the strap occurring at opposite ends of the body 10. The barbs 11 project laterally or 10 at acute angles from the body. As illustrated in the drawing the two barbs 11 project in the same general direction and are outwardly convergent to better enter or start in the crate or box to which the strap is applied. The outer ends of the 15 barbs 11 are suitably sharpened so that the barbs may be readily driven into wood or the like. The barbs 11 are preferably barbed or serrated at 13 to prevent or resist the working of the barbs and the withdrawal of the barbs from the box or 20 crate. It is to be noted that the two barbs 11 project laterally from the body 10 and lie in the same plane so that their weight tends to turn the body 10 about its longitudinal axis when the strap lies in a position where the barbs are 25 not in a vertical plane.

The laterally offset or projecting portions 12 of the strap are important features of the invention. While there may be as many projecting portions 12 as desired or necessary it will be found 30 that two spaced portions 12 will suffice in most instances. In the form of invention being described there are two portions 12 spaced inwardly equal distances from the barbs 11 on the ends of the body 10. The two portions 12 are 35 preferably alike or identical to be of substantially the same weight. In accordance with the invention it is preferred to have the portions 12 project from the opposite sides of the body 10 or in opposite directions, as best illustrated in Figs. 40 1 and 3 of the drawing. However, the portions 12 may project from the same side of the body 10, if desired. The portions 12 are integral parts of the body 10 being portions of the body bent or distorted to project laterally from the 45 body.

The formation or shape of the portions 12 may be varied as desired, it being important, however, to shape the portions 12 so that adjacent straps may closely nest together when arranged in a 50 pack or gang. It has been found desirable to make the portions 12 substantially V-shaped to each comprise two outwardly convergent parts 14. The inner and outer sides of the parts 14 are flat or provided with substantially flat surfaces 55 15. The flat surfaces 15 allow the portions 12 of adjacent straps to closely nest together whereby the bodies 10 of an assembly of straps may be in close parallel relation. Further, the flat cooperating surfaces 15 of the portions 12 of 60 two engaging straps of a gang or assembly assist in preventing turning of the straps about their individual axes and assist in accurately orienting the straps. It is important to note that the portions 12, projecting laterally from the body 10 65 and shaped to nest or fit together when the straps are arranged in an assembly, serve to definitely prevent relative longitudinal movement between the several straps of the assembly.

In accordance with the invention the laterally 70 projecting portions 12 project in or occur in planes at substantially right angles to the plane occupied by the barbs 11. This relationship between the barbs 11 and the laterally projecting portions 12 is important as it allows a multiplicity of the straps to be arranged in a group or

gang with the barbs 11 projecting in the same direction when the portions 12 lie in a common plane. The above described relationship between the laterally projecting portions 12 and the barbs 11 is such that the portions 12 may lie against the surface of a box or article when the strap is to be driven to prevent undesirable turning of the strap. As illustrated in the drawing, it is preferred to have the portions 12 project in opposite directions or from opposite sides of the body 10 15. The oppositely projecting portions 12 counterbalance one another so that the strap remains balanced except for the two barbs 11 projecting in the same general direction. Thus the provision of the laterally projecting portions 12 does not interfere with the action of the projecting barbs 11 which because of their weight cause the strap to turn by gravity when they leave the guides of the stapling machine. It is to be noted that the above described projecting portions 12 may be 20 easily and inexpensively formed and do not materially complicate the manufacture of the strap.

The pack or bundle of staples provided by the invention includes a multiplicity of the strap or straps nested one against the other and two clips 25 or binding members 20 holding the nested straps together for ready handling, shipping and insertion in the stapling machine.

Figs. 1 and 2 of the drawing illustrate the pack or assembly of straps of the character just 30 described held together by the two members 20. The several straps are nested or assembled with their barbs 11 projecting in the same direction and with their offset or lateral portions 12 nested 35 one within the other. The above described angular relationship between the barbs 11 and the portions 12 is such that the barbs 11 project laterally from the stack or assembly of the straps with the straps nested as just described. Thus 40 when the assembly is arranged in a vertical position the barbs 11 project substantially horizontally from the pack or gang of straps as illustrated in Figs. 1 and 2. As described above the laterally projecting portions 12 of the adjacent straps fit one within the other so that the bodies 45 10 of the straps may be parallel and in contact one with the other. It is important to note that the cooperating or nesting portions 12 of the stacked gang of straps prevent relative endwise movement of the straps and thus hold the barbs 50 11 in alignment. The cooperating parts or portions 12 also cooperate to prevent turning of the straps about their individual axes. The flat surfaces 55 15 of the portions 12 of the contiguous straps allow the portions 12 to closely fit together so that the bodies 10 of the adjacent straps may be in intimate contact. The portions 12 project from opposite sides of the straps so that the straps may be easily stacked without the necessity of turning any of them end for end to 60 have them nest together.

The clips or binding members 20 are provided to hold the stack or gang of straps together in a compact bundle or assembly for shipping, handling, etc., and for instant insertion in the stapling machine. The members 20 may be alike and may be simple sheet metal parts or strips. In accordance with the invention the members 20 are substantially U-shaped and are proportioned so that they may be arranged over the 70 gang of straps to have their arms 21 at opposite sides of the bundle or assembly. The side parts or arms 21 of the members 20 may be provided with ridges or corrugations 22 to make them more rigid. The arms 21 of the members 20 are in- 75

tegrally connected by intermediate portions or connecting portions 23 of the members. When the members 20 are arranged on the assembly or gang of straps their connecting portions 23 may 5 engage an end strap and the outer or free ends of their arms 21 may occur at the other end strap. The members 20 are preferably positioned to cover the nested together portions 12 of the stacked or assembled straps. The connecting 10 portions 23 of the binding members 20 are provided with transverse openings or slots 24. The two members 20 are preferably arranged on the bundle or gang of straps in corresponding positions, for example, as illustrated in Figs. 1 and 2, 15 the two members 20 may be arranged on the assembly to have their connecting portions 23 engage against the uppermost strap of the gang. The slot 24 in one of the members 20 is adapted to receive the laterally projecting portion 12 of 20 the uppermost strap. The opening or slot 24 cooperating with the projecting portion 12 of the uppermost strap prevents the binding member 20 from shifting or moving horizontally or transversely on the assembly. While I have illustrated 25 perforations in the form of slots for receiving the portions 12 it is apparent that openings of other characters may be provided in the members 20 to receive the portions 12. For example, recesses or depressions may be provided 30 to receive the portions 12 and the invention is not to be construed as limited to the specific form of openings 24 illustrated and the term "opening" employed in the claims is to be taken as meaning any form of opening suitable for 35 receiving the portions 12.

The invention includes means for removably holding the binding members 20 tightly engaged against the opposite sides of the stack or gang of straps to hold the straps in the proper nested 40 relation. The outer or free end of one arm 21 of each member 20 has two spaced fingers or tabs 25. The tabs 25 are adapted to be bent to engage over the end portions of the other arms 21 of the members 20. The tabs 25 when properly 45 bent or clinched down hold the two arms 21 of each member 20 in tight engagement with the opposite sides of the stack or assembly of straps. Thus the members 20 are effective in holding the plurality of straps in the proper assembled 50 relation. It is obvious, of course, that the lugs or tabs 25 engaging about the lowermost strap of the gang hold the connecting portions 23 of the members 20 in tight engagement with the uppermost strap whereby the members 20 hold the plurality of straps tightly nested together. The tabs 55 25 of each member 20 are spaced apart so that the tabs 25 of one of the members 20 are spaced at the opposite sides of the projecting portion 12 of the lowermost strap. This relationship is 60 clearly illustrated in Fig. 1 of the drawing. The lugs or tabs 25 engaging the opposite sides of the projecting portion 12 at the lower end of the gang effectively prevents transverse or longitudinal shifting of the binding member 20.

65 Following the insertion of the assembly or gang of stays or straps in the sapling or box binding machine the tabs 25 at the lower ends of the members 20 may be bent downwardly so that the members 20 may be readily withdrawn from the 70 straps by merely pulling the members upwardly. In this manner the members 20 may be easily and quickly disengaged from the stack or gang of straps following their insertion in the stapling or binding machine. It is to be noted that the members 20 arranged as described above are

spaced inwardly from the barbs 11 leaving the barbs entirely free and exposed so that they may be properly engaged by the guiding parts of the stapling or binding machine.

It is believed that the utility and practicability of the stays or straps and the assembly described above will be readily understood from the foregoing detailed description. The straps are simple integral members of wire or the like and are easy and inexpensive to manufacture. The provision of the laterally projecting portions 12 does not materially complicate the manufacture of the straps and the portions 12 may assist in orienting, guiding, or otherwise manipulating the straps during their manufacture. The straps 12 15 may be applied by a stapling or binding machine in the usual manner to engage over the sides of a box or crate and have their barbs 11 driven into the same. When applied in this manner the offset portions 12 of the straps lie 20 flat against a surface of the box or crate and if desired nails or small driving staples may be driven against them to assist in securing the larger straps to the box or crate. During shipping and handling of boxes and crates portions of the same often work or shift relative to one another and this movement has a tendency to disengage or spring the barbs of the straps out of place. Further, the contents of the crates sometimes shrink and allow the crate parts to become 30: loosened. The laterally projecting portions 12 of the straps allow the straps to flex or stretch when the crate and box parts work or become loosened in this manner and there is less tendency for the barbs 11 to work or spring free. 35: The straps having the offset portions 12 are in effect springs which automatically yield to compensate for shrinkage and expansion of the contents of the box or crate and which readily withstand shock.

The invention provides a stack, assembly or gang or straps bound together by the two binding members 20 so that they may be readily handled and shipped as a unit for immediate insertion in a stapling or binding machine. The bands or members 20 serve to confine the stack of straps so that their portions 12 are retained in the proper nested relation. With the portions 12 of the straps held in the nested relation the straps are prevented from shifting or working endwise relative to one another and are prevented from turning about their longitudinal axes. Thus the laterally projecting portions 12 of the strap bodies 10 serve to maintain the barbs 11 of the straps in the proper position and in alignment. With the barbs 11 projecting in the same direction and occurring in common planes the stack or gang of straps may be easily inserted in the guides of the stapling or binding machine. The members 20 are spaced inwardly a considerable distance from the barbs 11 and do not interfere with or engage the guiding parts of the box binding machine. The portion 12 of the end straps projecting from the upper and lower ends of the strap assembly cooperate with the opening 24 of 65 one member 20 and the tabs 25 of the other member 20 to definitely position the members and prevent undesirable displacement or shifting of the members. The laterally projecting portions 12 thus serve to locate and hold the members 70 20 in place. Following the insertion of the assembly or gang of straps in the machine the lugs or tabs 25 may be bent free whereupon the members 20 may be easily withdrawn upwardly from the straps. If desired, the laterally projecting 75

portions 12 of the bodies 10 may be engaged by suitable parts of the machine for the purpose of orienting, guiding, turning or otherwise manipulating the straps singly or in groups.

5. Fig. 6 illustrates a modified form of the invention. The stay or strap illustrated in Fig. 6 includes a body 10^a, barbs 11^a on the ends of the body 10^a and offset portions 12^a on the body. The body 10^a and the barbs 11^a may be identical with 10 the body and barbs of the above described strap.

10. The offset portions 12^a are spaced longitudinally of the body 10^a and there may be as many portions 12^a as deemed necessary. In the typical structure illustrated, there are two offset portions 12^a substantially equally spaced from the opposite ends of the body 10^a. The portions 12^a are alike and are integral parts of the wire body 10^a. In accordance with this form of the invention the offset portions 12^a are substantially 15. 20. Z-shaped, each including two outwardly convergent parts A and B, the parts A being straight integral extensions of one another as illustrated. In other words, each offset portion 12^a includes a part A lying at an angle to the long axis of the body 10^a and two parts B, each part B connecting an end of the part A with the body. The portions 12^a are preferably balanced, that is, they project equally from opposite sides of the body 10^a so that they do not tend to turn the 25. 30. body 10^a about its axis in one direction more than in the other direction. The two offset portions 12^a may be identical and lie in a common plane. The plane occupied by the offset portions 12^a is at right angles to the plane occupied by the barbs 11^a. The sides of the offset portions 12^a are flattened in the same manner as the above described portions 12 so that a multiplicity of the straps may be closely nested together with their portions 12^a closely fitting 35. one within the other.

40. The operation and the advantages of the strap illustrated in Fig. 6 are substantially the same as those of the above described embodiment of the invention. The portions 12^a projecting from both sides of the body 10^a may render the strap more resilient to better act as a spring. The type of strap illustrated in Fig. 6 has sufficient resiliency to successfully withstand shock when on the crate and to automatically compensate 45. 50. for working of the crate parts and shrinkage of the fruit or produce contained in the crate. It is believed that it will be apparent how the zig-zag portions 12^a impart this resilience to the strap. Straps of the type illustrated in Fig. 6 55. are adapted to be packed and shipped in a stack or gang similar to the assembly illustrated in

Figs. 1 and 2 and are adapted to be handled in the stapling or binding machine in the same manner as the previously described form of the invention.

Having described only typical preferred forms 5 and applications of my invention I do not wish to be limited or restricted to the specific details herein set forth, but wish to reserve to myself any variations or modifications that may appear to those skilled in the art or fall within the 10 scope of the following claims.

Having described my invention, I claim:

1. A retaining member for straps, each strap characterized by an elongated body and a laterally projecting portion between the ends of the 15. body, the projecting portions of adjacent straps nesting one within the other, said retaining member engaging about the gang of straps to hold said portions in the nesting relation, said member having an opening to receive said portion of an 20 end strap of the gang.

2. Binding means for a gang of straps, each strap characterized by an elongate body and longitudinally spaced laterally projecting portions spaced between the ends of the body, the 25. part of the body between said projecting portions being substantially straight, the projecting portions of adjacent straps nesting one within the other, the binding means comprising spaced binding members engaging about the gang, each 30. of said members cooperating with a set of the nested projecting portions to hold said portions in the nested relation, and spaced tabs on one end of each of the said members engaging over an end of the gang and cooperating with the 35. said projecting portion of an end strap of the gang.

3. Retaining means for a pack of straps, each strap characterized by an elongate body, barbs projecting laterally from the ends of the body 40 and extending in the same general direction, and two spaced laterally projecting portions on the body in a plane at an angle to the plane occupied by the barbs, said portions projecting in opposite directions, said retaining means comprising two spaced binding members wrapped about the pack of straps, each member having an opening, the opening of one member receiving a laterally projecting portion of a strap at one end of the pack, and tabs on the members wrapped about the other end of the pack to hold the members thereon, the tabs of the other member engaging the laterally projecting portion of the strap at said other end of the pack. 45. 50.

55. HERBERT HARVEY.
